Original application July 1, 1942, Serial No.
449,324. Divided and this application Decem-
ber 27, 1946, Serial No. 718,730

1 Claim. (Cl. 102—79)

(Granted under the act of March 3, 1883, as
amended April 30, 1928; 370 O. G. 757)

1

This invention relates to improvements in fuses for explosive projectiles, and the instant disclosure thereof is a division of an application for United States patent on Fuzes, filed by Raymond L. Graumann and William J. Donahue, Jr., now Patent 2,427,671, of September 23, 1947.

As brought out in that patent, a nose fuze is an explosive-loaded instrument for igniting or detonating the explosive filler of the projectile which carries it. The instant fuze, of which several forms are disclosed herein, is of the point-detonating type. Being such it is intended to function by igniting the burster charge on impact with the target.

For the purpose of classification said fuze is known as insensitive, that is to say, it is contrived particularly to function instantaneously on impact with structural members and armored parts of aircraft, or their equivalents. In comparison with this insensitivity there is a fuze distinguished as supersensitive, which is contrived to function upon impact with the lighter and less solid parts of the same aircraft. A fuze of the latter type is disclosed in a companion divisional application for patent for Nose fuze, filed by Raymond L. Graumann and William J. Donahue, Jr., filed December 27, 1946, Serial No. 718,729.

But regardless of the so-called insensitivity of the instant fuze, it contains an explosive train which must be protected against premature detonation. For this reason adequate safety features are embodied in order to forestall serious accidents during the transportation of projectiles, loading ammunition on board ships, loading projectiles into guns and, especially, while the projectile is subjected to the sudden and violent forces of being fired from the gun.

The safety features incorporated in the fuze render it both bore safe and detonator safe. That is to say, the fuze will not become armed in case the projectile encounters an obstruction in the bore of the gun, and its construction is such that should the detonator be set off prematurely the flash will not be communicated to the rest of the explosive train, consequently the explosive filler of the projectile will not be detonated.

These safety features are obtained by maintaining a break in the continuity of the explosive train of the fuze until the projectile actually begins its flight from the muzzle of the gun. Thereupon the centrifugal force developed by the spinning of the projectile becomes effective to establish the continuity of the explosive train, in other words to arm the fuze, in readiness for

2

the firing thereof when the projectile strikes the target.

Therefore, one of the objects of the invention is to provide a nose fuze which is contrived to insure the deferment of registration of the components of the explosive train with the firing pin or its equivalent until the projectile is subjected to centrifugal force such as will ordinarily be developed therein only upon firing said projectile from a gun.

A further object of the invention is to provide a fuze wherein a special feature resides in the relationship of the detonator-carrier or rotor to the body and nose cap of the projectile.

15 Other objects and advantages will appear in the following specification, reference being had to the accompanying drawings in which:

Fig. 1 is a longitudinal section of a nose fuze wherein the explosive train is detonated by the 20 shock of impact with a target;

Fig. 2 is a horizontal section of the fuze in Fig. 1, taken on the line 2—2 thereof;

Fig. 3 is a longitudinal section of a modification of the nose fuze, wherein the heavy nose or 25 sealing disk has an integrally attached firing pin, and

Fig. 4 is a longitudinal section of a further modification of the nose fuze wherein firing is caused through a blind nose cap.

30 In carrying out the invention provision is made of a fuze 25, so identified in each of the forms disclosed, each of said forms comprising a body 26 which has a base 27 threaded at 28 for screwing into the nose of an explosive projectile. The 35 body 26 includes a boss 29 provided with threads 30 to which a nose cap 31 is screwed. The body 26 contains a rectilinear kerf 32 which is occupied in part by a circular detonator-carrier disk 33.

40 This carrier is movable by centrifugal force from an initially unarmed or safe position (Fig. 2) to an armed or firing position wherein the detonator is aligned with the axis of the fuze and with the other elements of the explosive train.

45 Detent means is used in each form of the invention to hold the carrier in said unarmed position.

An internally threaded bore 34 in the rear of base 27 provides the mounting for a booster thimble 35. The thimble forms a backing for the kerf 32. A booster charge 36 is held in the thimble by suitable means. Communication between the booster charge and the kerf 32 is had through a lead-in 37 which, with the detonator 38 fitted in the carrier 33, completes what is referred to above as the explosive train.

Initially the detonator 38 is held out of registration with the lead-in 37 by the previously mentioned detent means which engage the carrier. Radially extending lateral bores 39 intersect the chamber 32 in an off-center position with reference to the carrier or rotor 33. These bores emerge at the exterior of the boss 29. The detent means comprise cylindrical plugs 40 which slidably fit the bores 39. They have pin ends 41 which occupy recesses 42 in the opposite plane 10 faces of the rotor to prevent its turning from the unarmed position. A sufficiently high degree of centrifugal force, such as is reached only after the projectile is fired from the muzzle of the gun, will displace the detents and free the rotor 15 from turning to the armed position, it being the counterweights 43 (Fig. 2) which respond to the force to do the turning.

Springs 44 bear at their inner ends on the detent means 40 and at their outer ends against 20 ferrules 45. The ferrules provide flat bases for the springs which are denied them by the breaking through of the bores 39 into the thread course. The nose cap 31 when screwed in place 25 confines the detent means and their accessories.

A chamber 46 in the nose cap 31 includes a front flat wall which provides a contact for the protruding part of the carrier 33. The latter is housed approximately half and half in the common chamber of the boss 29 and nose cap 31, 30 wherein it has a four-point bearing provided by its perimetric contacts at the front flat wall, just mentioned, the lateral extremities of the kerf 32 (Fig. 2) and the backing afforded by the thimble 35. The chief attribute of this arrangement which occurs in each of the forms, is the compactness of the fuze, and the avoidance of having to do fine and expensive machine work for the proper emplacement of the rotor 33.

Detailed reference is now made to each of the forms to explain distinguishing features. In Figs. 1 and 2 a sealing disk 47 is held in place in a rabbet 48 by crimping a thin annular edge 49 of the nose cap inwardly and over. The rabbet is the counterbore of a cylindrical hole 50 in the point of the nose cap. The base of this hole has a central orifice 51, partly conical and partly cylindrical as shown, leading into the chamber 46 and so into communication with the detonator 38 when in line. The method of firing is by shock. That is to say, upon impact of the nose with the target, the shock imparted to the then registering detonator ignites the latter. The flash is transmitted to the explosive train, thence back to the explosive filler.

In Fig. 3 the cylindrical hole 50 has a rabbet 48 deeper than the corresponding rabbet in Figs.

1 and 2, to accommodate a heavy sealing or nose disk 52. In this instance the disk has an integral firing pin 53 which fits the orifice 51. Only the cylindrical part of the orifice is used, the conical part in Figs. 1 and 2 being omitted. The method of firing the fuze in Fig. 3 is the same as described for Figs. 1 and 2, namely, by the shock of impact with the target.

Fig. 4 is the simplest of the three forms. The nose cap 31 terminates in a blind and blunt end 54 which is adapted to strike the target. When this happens the detonator 38, then in registering position, is initiated by the ensuing violent shock imparted to it by the blind nose.

The invention described herein may be manufactured and used by or for the Government of the United States of America for governmental purposes without the payment of any royalties thereon or therefor.

We claim:

In a fuze, a centrifugally turnable detonator-carrier disk, a body having a rectilinear kerf cut through it from a back surface thereof, delineating a pair of lateral parallel walls, by which kerf part of the disk is contained so that the rim of the disk contacts the forward ends only of said parallel walls with a two-point contact, said disk being insertable into the kerf from said back surface and having the adjacent part of its rim substantially flush with said back surface, a nose cap fitted onto the body, having a chamber containing the remaining part of the disk and having a wall with which the front part of the rim of the disk contacts to make a third-point contact, and a booster-carrying thimble fitted into the rear of the body into engagement with the back surface of the body, closing the rear of the kerf and providing a fourth-point contact for the disk.
